(57) **CLAIM**

The ornamental design for a basket web, as shown and described.

DESCRIPTION

FIG. 1 is a front view of a basket web.

FIG. 2 is a rear view of the basket web.

FIG. 3 is a left side view of the basket web.

FIG. 4 is a right side view of the basket web.

FIG. 5 is a top view of the basket web.

FIG. 6 is a bottom view of the basket web; and,

FIG. 7 is a perspective view of a basket web in condition of use with a baseball glove, the glove shown in broken lines and forming no part of the claimed design.

The broken lines shown on the basket web in the drawings are understood to represent stitching.
